UNITED STATES PATENT OFFICE.

EDWARD MINNICK, OF SPRING HILLS, OHIO.

FENCE-POST.

SPECIFICATION forming part of Letters Patent No. 444,781, dated January 13, 1891.

Application filed March 31, 1890. Serial No. 346,052. (No model.)

To all whom it may concern:

Be it known that I, EDWARD MINNICK, a citizen of the United States, and a resident of Spring Hills, in the county of Champaign 5 and State of Ohio, have invented certain new and useful Improvements in Iron Fence-Posts; and I do declare the following to be a full, clear, and exact description of the invention, such as will enable others skilled in the art to 10 to which it appertains to make and use the same, reference being had to the accompanying drawings, and to letters of reference marked thereon, which form a part of this specification.

15 Figure 1 of the drawings is a representation of the fence-post, and is a perspective view. Fig. 2 is a plan view of the casting. Fig. 3 is a view of the fence, showing the general disposition of the posts.

20 This invention has relation to iron fence-posts, especially such as are designed to be used in constructing wire fences; and the invention consists in the construction and novel combination of parts, all as hereinafter set forth.

25 In the accompanying drawings, the letter A designates the main shank or bar of the post, and B is the lower extension, which is in the form of a blade at right angles to the 30 plane of the main bar, having its sides C C, projecting beyond the lower portions of the faces D D of the main post, as shown. The main portion of the post has parallel sides.

G indicates a casting which is vertically 35 adjustable upon the main shank or post A, and designed to be driven into the ground in order to securely anchor the post in position. The brace-casting G is constructed with two outwardly-concave opposite flanges H, connected by a vertically-perforated transverse web a. The perforation b of the web a receives the main shank A of the post whereon the brace-casting may be vertically adjusted 40 to accommodate the setting of the posts to the depressions and raised portions of the ground.

45 The flanges H are adapted to stand adjacently to the edges of the post A and at right angles to its width. The flanges on each side of the web are at right angles to the broader 50 parallel sides of the post, and they are pointed

and beveled on their edges to facilitate driving into the ground, said beveled edges also aiding to pack the earth between the flanges. Their outer faces are concave and their inner faces are convex from side to side, and 55 when driven into the ground they have a wedging action presenting a broad resisting surface of such form that the fence is enabled to withstand the force of the highest winds, whatever be their direction. It will 60 be observed that by the adjustability of these brace-castings upon the posts, the latter can be located in constructing a fence, some in high places and others in low places, and still carry the lines of wires in straight or nearly 65 straight parallel lines, thus permitting them to be stretched when necessary without danger of drawing from the ground such posts as may be set in lower ground. The brace- 70 castings being movable can be driven down so that their upper edges will be flush with the surface of the ground in every case without reference to the height of the post above the ground. The post and casting being separate, transportation is facilitated and the 75 labor of construction made lighter as the posts proper may be set in position first, and then the brace-castings slipped on from the top and driven in place, when the posts will be ready for wiring.

80 What I claim, and desire to secure by Letters Patent, is—

The thin parallel-sided fence-post, having the point portion setting in a plane in the axis of the post but at right angles to its 85 width, as described, and the adjustable loose bracing-casting having the elongated bearing to engage the post and provided with outwardly-concave flanges adjacent to the edges of said post and standing at right angles to 90 its width and beveled on their inside edges to aid in the packing of the earth between the flanges, as shown.

In testimony whereof I affix my signature in presence of two witnesses.

EDWARD MINNICK.

Witnesses:

SAML. TAYLOR,
IRA KIRKWOOD.
